[57] CLAIM

The ornamental design for a shoulder strap repositioner for vehicle seat belt assembly, as shown.

DESCRIPTION

FIG. 1 is a three-dimensional view, generally of the front, of a shoulder strap repositioner for vehicle seat belt assemblies, showing my new design;

FIG. 2 is a front elevational view thereof;

FIG. 3 is a rear elevational view thereof;

FIG. 4 is a left side elevational view thereof, the right side being a mirror image;

FIG. 5 is a top plan view thereof; and,

FIG. 6 is a bottom plan view thereof.
